UNITED STATES PATENT OFFICE.

EDWARD MELVILLE HUGGINS, OF NEW YORK, N. Y., ASSIGNOR TO THE SNEAD & CO.
IRON WORKS, OF JERSEY CITY, NEW JERSEY, A CORPORATION OF NEW JERSEY.

ROLL RAMMING APPARATUS.

1,176,454.

Specification of Letters Patent. Patented Mar. 21, 1916.

Application filed November 19, 1914. Serial No. 872,895.

To all whom it may concern:

Be it known that I, EDWARD MELVILLE HUGGINS, a citizen of the United States, residing in New York, county of New York and State of New York, have invented certain new and useful Improvements in Roll Ramming Apparatus, of which the following is a specification.

This invention relates to roll ramming apparatus, and it has for one of its primary objects the combination with roll ramming apparatus of an improved mechanism whereby a plurality of flasks may be conveniently and expeditiously handled and rammed in such manner that the workmen carrying on the different steps of the operation do not interfere with one another.

Another object of the invention has reference to the provision of a shiftable mold table coöperating with a roll ramming machine during the ramming operation and movable to facilitate the handling of the mold parts.

The foregoing, together with such other objects as may hereinafter appear or are incident to my invention, I attain by means of a construction which I have illustrated in preferred form in the accompanying drawings, wherein:

Figure 1 is a diagrammatic illustration of a roll ramming mechanism showing the application of my improvements thereto, the parts being shown in plan view; Fig. 2 is a side elevation of certain parts of the ramming mechanism; Fig. 3 is an end view of Fig. 1; and Fig. 4 is a side elevation of my improved mold table apparatus.

Attention is first directed to the roll ramming apparatus, of which I have illustrated only those parts which are necessary to point out the functional and coöperative characteristics of my improvements. The roll ramming apparatus comprises a base block, 7, at the forward end of which is a pair of stationary tracks 8, preferably composed of angle irons. A ramming roll 9 of usual construction is adapted to ride on these tracks, and may be operated in any desired manner, although I prefer to actuate it by fluid pressure. In the construction shown, the roll is provided with a forked yoke 10, to which is secured a piston rod 11 operated by a piston (not shown) working in the cylinder 12. In order to compensate for the vertical movement which takes place when the roll

rides onto and from off the flask, the cylinder 12 is trunnioned in the brackets 13 carried on the base block 7. At the forward end of the ramming apparatus, I provide a pair of movable tracks 14, preferably of a tilting type hinged to the base block by means of the bracket member 15, as at 16. The operation and functions of the movable tracks will be further considered hereinafter.

Adjacent to the forward end of the ramming apparatus, I provide a mold table supporting means which in the preferred embodiment of my invention comprises a pair of tracks 17 extending transversely of the ramming apparatus and supported in any suitable manner, as by the foundation members 18, (see Figs. 3 and 4). These tracks are adapted to support movable mold tables of which there are two, A and B, respectively. The mold tables are provided with wheels 19, flanged to engage the tracks to prevent relative lateral displacement, and at the top the tables are provided with plane surfaces to support a pattern plate and a flask 20.

While there are but two mold tables, the supporting mechanism therefor has three operative stations, a central one in substantial alignment with the molding apparatus and a station located on either side thereof. In order to maintain the tables in their respective operative stations, I provide three sets of molds or grooves, 21, 22, and 23, in the tracks 17 which are engaged by the wheels of the tables and serve as a means to position them. The tracks are also provided with three stops 24 which are adapted to be engaged by the lugs or abutments 25 formed on the tables. These abutments are oppositely positioned with respect to each other and lie on opposite sides of the center line of the respective movable mold tables, so that the central stop serves to limit the inward movement of both tables to the central station. The end stops limit the movement of the tables to the outer stations. The purpose of the provision of the notches in the tracks 17 is to prevent accidental shifting of the tables during the different molding operations. It will be seen from the foregoing that each table assumes two operative positions, one at the center of the apparatus, and one to the side thereof, as will be clear from inspection of Figs. 1 and 3 in

which table A is shown in central position in full lines and in side or outer position in dotted lines.

Reference is again directed to the movable tracks 14. When one of the movable mold tables is to be brought to the central station in alignment with the molding apparatus, the tracks are swung to an inoperative position in which they lie clear of the mold tables and their supporting mechanism, the roll in such case being also retracted to inoperative position, resting on the stationary tracks 8. After the table with its flask has been moved to central position, the tracks 14 are lowered until they rest upon and are supported by the top edges of the flask, as shown in Fig. 3 in dotted lines. The flask being filled with sand, the roll is then advanced from the stationary tracks onto the movable tracks and across the flask to ram the sand, after which it is retracted back over the flask to inoperative position. The tracks 14 are then swung clear and the mold table with the rammed mold is retracted to its respective outer station where the mold is drawn. A new flask is then placed in position over a pattern, the facing sand is riddled on, and the flask filled with sand, after which this table is again ready for another ramming operation. It will be understood that while one table is in central position for the ramming operation, the other table is at its outer station being prepared for a ramming operation, after its completed mold has been removed. It will be noted that the mold table supporting means in reality forms a part of the ramming apparatus.

It will be apparent that the combination of a movable flask supporting table or device, with a roll ramming apparatus having a movable track adapted to support the roll over the flask during the ramming operation, is very advantageous, in that the facility with which the parts may be handled and the operations carried out is greatly increased. The chief advantage of the preferred embodiment of the invention is that the mold preparing, mold ramming, and mold drawing operations may be carried on simultaneously, in a convenient and expeditious manner, without interference between the respective workmen. Greater efficiency and economy is thus insured.

The arrangement of the mold table supporting mechanism transversely of the ramming apparatus has a further advantage in that the tables are held against displacement which would otherwise be occasioned by the thrust exerted by the roll, as it is reciprocated. This is prevented by the engagement of the wheel flanges with the rails 17. The grooves in the rails are sufficient to prevent accidental lateral displacement of the mold tables under load. Lateral and longitudinal displacement of the flasks relative to the

mold tables is prevented by means of the ears 26 and 27 and the removable pins 28 (see Fig. 4).

I do not intend to limit myself to the precise construction shown, as variations can be made without departing from the spirit of the invention as defined.

A marked advantage incident to the use of a mold supporting table which is not fast or permanently attached but which on the contrary is capable of being removed from the machine, resides in the fact that mold supporting tables of different sizes may be used in order to accommodate flasks of different sizes. For example, since the plane of movement of the roll is relatively fixed, a shallow supporting table will be substituted where a deep flask is to be rammed, and vice versa.

I claim:—

1. The combination in molding apparatus of a roll ramming mechanism having a reciprocating ramming roll and a support for the roll when the latter is retracted to an inoperative position, a shiftable mold supporting table adapted to be brought into alignment with the roll ramming mechanism, and a flask carried on said table and adapted to serve as means from which the roll may be supported as the latter is reciprocated during the ramming operation.

2. The combination in molding apparatus of a roll ramming mechanism having a reciprocating ramming roll and a support for the roll when the latter is retracted to an inoperative position, a mold table supporting means located adjacent to said support, a shiftable mold table mounted on said supporting means for movement to an operative position adjacent to and in alignment with the ramming mechanism, and a flask on said table adapted to serve as a means from which the roll may be supported as the latter is reciprocated during the ramming operation.

3. The combination in molding apparatus of a roll ramming mechanism having a reciprocating ramming roll and a support for the roll when the latter is retracted to an inoperative position, a mold table supporting means located adjacent to said support and extending transversely thereof, a shiftable mold table mounted on said supporting means for movement into and out of alignment with the ramming mechanism, and a flask on said table adapted to serve as a means from which the roll may be supported as the latter is reciprocated during the ramming operation.

4. A molding apparatus comprising in combination a roll ramming mechanism having a reciprocating ramming roll, a transportable mold supporting table cooperating with said ramming mechanism when moved into alignment therewith, a flask on

5 said table, means for advancing the roll across the flask to ram the sand therein, and a supporting means independent from said mold table for supporting the roll when the latter is moved to an inoperative position clear of the table.

10 5. A roll ramming apparatus comprising in combination a reciprocating roll, a support therefor adapted to support the roll in retracted position, a movable mold table adapted to be brought into alinement with the said support, a flask on the table, and a movable roll supporting member adapted to rest on the flask when moved to operative position whereby the roll may be advanced from its support over the flask and to lie clear of the mold table when moved to an inoperative position whereby the mold table with its flask may be removed.

15 20 6. A roll ramming apparatus comprising in combination a reciprocating roll, a support therefor adapted to support the roll in retracted position, a movable mold table adapted to be brought into alinement with the said support, a flask on the table, and a movable roll supporting member hinged to said support and adapted to rest on the flask when moved to operative position whereby the roll may be advanced from its support over the flask and to lie clear of the mold table when moved to an inoperative position whereby the mold table with its flask may be removed.

25 30 35 7. A roll ramming apparatus comprising in combination a reciprocating roll, a support therefor, a mold table supporting device adjacent to said support and extending transversely of the ramming apparatus, and a plurality of shiftable mold supporting tables mounted on said supporting device for movement successively into and out of alinement with the ramming apparatus whereby the roll may be advanced from off its support for ramming the molds.

40 45 50 8. A roll ramming apparatus comprising in combination a reciprocating roll, a support therefor, and a plurality of mold supporting tables movable successively into and out of alinement with said support whereby the roll may be advanced for ramming the molds.

55 9. A roll ramming apparatus comprising in combination a reciprocating roll, a support therefor, a plurality of mold supporting tables movable successively into and out of alinement with said support whereby the roll may be advanced for ramming the molds, and a second movable support for the roll adapted when moved to operative position to support the roll for movement across a mold table and when moved to inoperative position to permit of the movement of the mold tables.

60 55 10. A roll ramming apparatus comprising in combination a reciprocating roll, a sup-

port therefor, a mold table supporting device adjacent to said support and extending transversely of the ramming apparatus, said device having three operative stations, a central one in alinement with the roll support and one on each side thereof, a pair of mold tables movably mounted on said device for movement from a side station to the central one and vice versa, and means for advancing the roll to ram a mold when a table has been moved to central position.

15 16 11. A roll ramming apparatus comprising in combination a reciprocating roll, a support therefor, a mold table supporting device adjacent to said support and extending transversely of the ramming apparatus, said device having three operative stations, a central one in alinement with the roll support and one on each side thereof, a pair of mold tables movably mounted on said device for movement from a side station to the central one and vice versa, means for advancing the roll to ram a mold when a table has been moved to central position, and means to prevent the tables from being displaced by the thrust of the roll.

20 25 30 35 12. A roll ramming apparatus comprising in combination a reciprocating roll, a support therefor, a mold table supporting device adjacent to said support and extending transversely of the ramming apparatus, said device having three operative stations, a central one in alinement with the roll support and one on each side thereof, a pair of mold tables movably mounted on said device for movement from a side station to the central one and vice versa, means for advancing the roll to ram a mold when a table has been moved to central position, and means for maintaining the tables in position in any of said operative stations.

40 45 50 55 13. A roll ramming apparatus comprising in combination a reciprocating roll, a support therefor, a mold table supporting device adjacent to said support and extending transversely of the ramming apparatus, said device having three operative stations, a central one in alinement with the roll support and one on each side thereof, a pair of mold tables movably mounted on said device for movement from a side station to the central one and vice versa, means for advancing the roll to ram a mold when a table has been moved to central position, a flask on a table, and means for preventing relative displacement of the flask and table as the roll is being operated.

60 65 70 75 14. A roll ramming apparatus comprising in combination a reciprocating roll, a support therefor, a mold table supporting device adjacent to said support and extending transversely thereof, a pair of mold tables movably mounted on said device, said device being provided with three operative stations, a central one in alinement with the

roll support and one on each side thereof, and stop mechanism adapted to limit the movement of the tables and arranged to permit each table to be moved from a side station to the central station and back to said side station.

15. A roll ramming apparatus comprising in combination a reciprocating roll, a support therefor adapted to support the roll in retracted position, a movable mold table adapted to be brought into alinement with the said support, a flask on the table, and a movable roll supporting member adapted to extend over the flask when moved to operative position whereby the roll may be advanced from its support over the flask and to lie clear of the mold table when moved to an inoperative position.

16. A roll ramming apparatus comprising in combination a reciprocating roll, a support for the roll, and a coöperating movable mold supporting table adapted to carry a flask and movable into alinement with the roll for the ramming operation and also to a point removed therefrom to facilitate the handling of the mold parts.

17. A roll ramming apparatus comprising in combination a reciprocating roll, a support therefor adapted to support the roll in

retracted position, a movable mold table 30 adapted to be brought into alinement with the said support, a flask on the table, and a movable roll supporting member adapted to rest on the flask when moved to operative position.

18. A roll ramming apparatus comprising in combination a reciprocating roll, a support therefor, a mold table supporting device adjacent to said support and extending transversely of the ramming apparatus, a 40 plurality of shiftable mold supporting tables mounted on said supporting device for movement into and out of alinement with the ramming apparatus, and means for advancing the roll.

19. A roll ramming apparatus comprising in combustion, a roll, a support therefor, a plurality of mold supporting tables movable successively into and out of alinement with said support, and means for advancing the 50 roll.

In testimony whereof I have hereunto signed my name in the presence of the two subscribed witnesses.

EDWARD MELVILLE HUGGINS.
